UNITED STATES PATENT OFFICE.

ORSON E. JESSUP, OF SPRINGFIELD, MASSACHUSETTS.

MACHINE FOR STRAIGHTENING GUN-BARRELS.

1,240,576.

Specification of Letters Patent. Patented Sept. 18, 1917.

Application filed April 23, 1917. Serial No. 163,789.

To all whom it may concern:

Be it known that I, ORSON E. JESSUP, a citizen of the United States of America, residing in the city of Springfield, county 5 of Hampden, and State of Massachusetts, have invented certain new and useful Improvements in Machines for Straightening Gun-Barrels, of which the following is a specification.

10 This invention relates to improvements in machines for straightening gun barrels. An object of the invention is to provide a device that will enable the operator to accurately and quickly straighten the barrel of a gun

15 so that the bore therethrough is accurately formed. The invention, broadly considered, comprises a pair of adjustable anvils or blocks for supporting the barrel during the straightening process and with means for

20 adjustably raising and lowering the barrel as a whole, said blocks being designed to bring the line of sight through the bore to accurately coincide with the target or sighting mark. Means comprising rotatable hammers

25 are located above the barrel which successively engage the barrel between its supports for straightening the same. Means are also provided for varying the direction of rotation of the rotatable hammers, and

30 means are provided for permitting the rotatable hammers to be raised and lowered by the operator for varying the force of the blow.

Referring to the drawings:

35 Figure 1 is a plan view showing the driving devices for operating the hammers and means for raising and lowering the same and the adjustable means for rendering the machine inoperative;

40 Fig. 2 is a side elevational view of Fig. 1 showing the means for adjusting the table or platform as a whole on which the barrel to be straightened is placed, also the fixed internal gear which causes the rotatable 45 hammers to operate; and

45 Fig. 3 is a front elevational view looking toward Fig. 2 from the left, indicating one of the rotatable hammers engaging the gun barrel, and the means for supporting the 50 hammer carrying frame.

Referring to the drawings in detail: The base part of the machine is indicated at 1 and the platform part is indicated at 2 which is pivotally connected to the base 1 by means of the depending projection 3 and the upwardly extending projection 4, only

one of which is shown, the pivot being indicated at 5. Extending transversely across the forward end of the machine is a shaft 6 to which is secured the hand wheel 7 having the spokes 8. Secured to the ends of the shaft 6 are elliptical or oval shaped gears 9 which engage gears 10 that are rotatably mounted in the depending hangers 11. By turning the hand wheel 7 the table 2 can be accurately raised and lowered as desired. A stiff contractile coiled spring 12 has its opposite ends attached to the base piece 1 and the platform 2, whereby the gears 9 and 10 are always held in mesh and the table 2 is drawn downward and firmly held in the adjusted position. Adjustably mounted on the table 2 are the anvils or brackets 13 which support the ends of the gun barrel 14 that is to be straightened. These brackets, as clearly shown in Fig. 3, have depending portions 15 and nuts 16 for securing the same in place. They are also provided with set screws 17 for adjusting the anvils whereby the line of sight through the barrel may be accurately adjusted. This line of sight is shown at 18 and the target point at 19 on the wall. The gun barrel 18 that is to be straightened is placed on these anvils and then the hand wheel 7 is rotated to raise or lower the platform 2 as a whole to bring the barrel 18 into a position that is approximately correct. It is to be understood that the anvils 13 are then adjusted up or down independently of the platform to finally position the barrel 90 that is to be straightened.

Referring now to the construction of the rotatable hammers which engage the barrel that is to be straightened: The source of power is indicated by the belt 20 which passes over a pulley 21. This pulley is secured to the countershaft 22 which is adjustably mounted in the bearings 23 and moved therein by any suitable means for varying the speed of the machine. Carried by the shaft 22 is a frictional disk 24 preferably having its periphery faced with leather. This disk engages a second disk 25 which is mounted on a jack-shaft 26 that carries the cone pulleys 27 which in turn are belted to the cone pulleys 28 by the belt indicated at 29. Pulleys 28 are secured to the shaft 30 at the forward end of the machine. 31 indicates an internal gear that is fixed against rotation and through which the shaft 30 loosely passes. 32 and 33 are shafts that are rotatably mounted in the

rotatable disks 34. On the ends of these shafts are secured the pinions 35 which mesh with the teeth of the gear 31. The shafts 32 have secured thereon the circular 5 disk shaped hammers 36 which strike the gun barrel 18 for straightening the same. The disks 34 serve therefore, as a carrying frame which rotates as a whole and the pinions 35 are carried around by this frame 10 on the inside of the gear 31, whereby the hammers 36 are rapidly rotated. For the purpose of raising and lowering the shaft 30 and consequently the hammers 36 a lever 37 is provided which is pivotally attached 15 to the standard 38 and intermediate its ends it is attached to the shaft 30. The shaft 30 is mounted in the forward ends of the side rods 39 which form part of a swinging frame. 40 are cross bars of this frame. The 20 side bars are connected to an end bar or rod 41 that is pivotally mounted in the upright bearings 42. This frame is drawn downward by means of the springs 43 which are attached to the bearings in which the 25 shaft 30 is mounted. The lower end of the springs is connected to a depending rod 44, which rod extends downward through the platform 2 and has the adjustable nuts 45 on the lower ends of the same, whereby the 30 tension of the springs 43 may be adjusted. In addition, provision is made for placing weights 46 and thumb nuts 47 on the upper ends of the rods 48. The weights are for counterbalancing the swinging frame 35 against the tension of the springs 43 and 50. Attached to the opposite ends of the bearings in which the shaft 30 is mounted are wires 49 having coiled springs 50 therein which springs are attached to rod 51 that 40 extends upward to the ceiling overhead to which they are attached, whereby the whole frame comprising the side members, cross bars 40 and shaft 30 which carries the revolving hammers 36, may be readily raised 45 and lowered by the lever, it being understood that the springs 50 are stronger than the springs 43 whereby the frame will be elevated when the operator removes his hand from the lever 37. For the purpose 50 of disengaging the driving disks 24 and 25 the handle 52 is provided as shown in Fig. 1, which is suitably connected to the shaft 26 by means of the bar 53 that extends downward through the openings 54 in the 55 platform 2, the lower end of this rod being connected to the bar 52 below the platform whereby the disks 24 and 25 may be separated to shut off the source of power.

What I claim is:

60 1. In a machine of the kind described the combination with an adjustable table on which the article to be straightened is placed, of a plurality of bodily revolving hammers arranged for imparting blows 65 thereto, means for rotating said hammers

independently of their bodily rotation, and means for manually moving the hammers toward the article for varying the force of the blow which is imparted to the article to be straightened. 70

2. The combination with an adjustable table on which the gun barrel to be straightened is placed, of means for varying the position of the supporting means for said barrel for alining the sight of the barrel, revolving hammers for imparting blows to the barrel, manually operable means for moving the hammers for varying the force of the blow, and a swinging frame for supporting the revolute hammers. 75

3. The combination in a machine of the kind described, of a supporting table, sight adjusting anvils thereon for receiving the barrel to be straightened, a revolving frame, revolute hammers carried by said frame, means for adjusting the table as a whole, and means for changing the direction of rotation of said frame and hammers, said table adjusting means including a pair of elliptical shaped gears located below the 90 table and engaging a pair of gears on said table. 80

4. The combination with the adjustable table of a gun-barrel straightening machine, of means for adjusting the table, revolving 95 hammers for imparting blows to the barrel, means for changing the direction of rotation of the blows, and a frame pivoted at one end in which the hammers are supported for elevating the hammers, as described. 100

5. A gun-barrel straightening machine, comprising in combination, an adjustable platform having supports for receiving and supporting the barrel to be straightened, means for individually adjusting each support, disk-shaped hammers for imparting blows to the barrel to be straightened, a pair of revolute disks, shafts for revolutely supporting the hammers and mounted in the 110 revolute disks, a fixed internal gear, pinions on the hammer supporting shafts engaging the teeth of fixed gear, and means for revolving the pair of disks, whereby the disk-shaped hammers will be revolved, and carried into contacting relation with the 115 gun-barrel. 120

6. A gun-barrel straightening machine comprising, in combination, a platform for supporting the barrel, a frame pivotally connected to the platform and carrying the hammers which are designed to impart blows to the barrel, means comprising suspension springs and weights for balancing said frame, and means for imparting rotary motion to the hammers. 125

7. A gun-barrel straightening machine comprising, in combination, an adjustable table for supporting the barrel to be straightened, a balanced frame for support- 130

ing the hammers, means for imparting rotary motion to the hammers, comprising a revolute frame, revolute shafts carried by the revolute frame, a fixed gear with operative connecting means between said gear and the revolute shafts, whereby when the revolute frame is rotated the hammers will have rotary motion imparted thereto as described, and means for rotating the revolute frame.

8. A gun-barrel straightening machine comprising in combination with the supporting platform, of means for imparting a revolving blow to the barrel, comprising a revolving frame in which the hammers are revolutely mounted, a fixed internal

gear, pinions engaging the teeth of said gear for revolving the hammers as said frame is rotated, and means for changing the direction of rotation of said frame. 20

9. A straightening machine comprising in combination with the supporting table, of means comprising eccentrically shaped gears for adjusting the table, means for adjustably supporting the barrel to be straightened, revolving hammers for engaging the barrel, manually operated means for varying the force of the blows imparted to the barrel, means for changing the direction of rotation of the hammers. 25
